(57) **CLAIM**

The ornamental design for a massager housing lid, as shown and described.

DESCRIPTION

FIG. 1 is a top perspective view of the massager housing lid showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom plan view thereof.

The broken line disclosures of the lower housing portion, massager element, cord and cord protector illustrate the environment. None of the broken lines forms part of the claimed design.

1 Claim, 4 Drawing Sheets
